DOUBLE EXPOSURE PHOTOGRAPHING AND DEVELOPING APPARATUS

George N. Pifer, Cleveland Heights, Ohio, assignor to Speedtype, Inc., Cleveland, Ohio, a corporation

Application December 4, 1944, Serial No. 566,429

3 Claims. (Cl. 95—14)

1

This invention relates to a photographic apparatus, preferably referred to as Instant Phototure, efficient, rapid and operative on the open counter without darkroom, or booth, with all the developing and processing being done in open daylight under a red safe-glass, in full view of the sitter being photographed, and of any onlooker.

The object of the present invention is to utilize, with certain improvements and modifications, the aerated instantaneous and cleanly application of the developing solutions, with the quick-drying and moisture-proof photographic paper base as disclosed in my Patent No. 1,682,931. However, in all other respects I provide a device applicable to the many different current new needs in the photographic field, eliminating the high cost of manufacture and intricate mechanisms, and even motive power, and making same operative by the simple means of pressing a few buttons without wetting a hand.

A further object is a multiplicity of uses and adaptations varying from a speedy method for photographic identification with complete index registration, and making the photograph fool-proof by special or specific designs, emblem or fingerprint, etc., to studio portraiture work by the photographer right over the public shopping counter, and, which enables him to show his sitter immediate proofs from the sittings that are being made.

These objects are obtained with almost the entire elimination of mechanical motive power, as seen in the identification procedure which numbers, autographs, imposes upon a film negative and print, any distinctive inscription or mark in conjunction with a preprinted registration card for filing record, and completes the operation and duplicates the photographic prints in a speedy manner. Aside from its variable applications with immediate processing of the film and duplicating prints therefrom, the present invention is also operative singly as a bare camera, for exposures on the film only, or, operative singly as a copying and a projection camera—the developing and fixing being done by the regular darkroom method—in other words dispensing with the solutions and atomizing processing. All the novel features and objects accomplished by the present invention will be summarized and described in detail in the following specification and as set forth in the appended claims.

In the accompanying sheets of drawings,

Fig. 1 is a perspective view of my improved photographic apparatus;

Fig. 2 is an enlarged view, partly in section and

partly in elevation, omitting the outer lamp and the standards which support it;

Fig. 3 is an enlarged perspective view, partly diagrammatic, showing certain parts of the equipment illustrating how the first photographic impression is made on the film and also how the second photographic impression is made on the film;

Fig. 4 is an enlarged sectional view largely diagrammatic of the mechanism by which the atomized or aerated developing solutions are applied to the film;

Fig. 5 is an enlarged perspective view largely diagrammatic illustrating the manner in which the prints taken from the negative, are developed by the aerated solutions;

Fig. 6 represents an original index preprinted registration card, with any special data or imprint, on that portion which is to be photographed;

Fig. 7 is a finished photographic card which is produced in my machine;

Fig. 8 is an enlarged view of a portion of a film 20, on which the facial image has been applied and exposed, and a transparent slide with a black-out section adapted to be positioned over the image for the second photographic impression;

Fig. 9 is a view on an enlarged scale, showing the section of the film with the transparent slide of the Figure 8, covering the facial image for the second photographic impression, and illustrating the data that is to be applied and superimposed, for the second exposure; and

Fig. 10 is a view similar to Figs. 8 and 9 showing a modification.

Before describing the machine in detail, I wish to give the sequence of operations to make the double-exposed-negative, and prints. Looking at 40 the exterior view of Fig. 1, the sitter is before the lens and the attendant momentarily presses a switch 11c in a lamp circuit which lights the sitter; then the attendant turns a lever clockwise which trips and opens the shutter on the portrait lens and rolls the film to the adjacent chamber in focal line with the projection lens, shown in Fig. 2, at the same time placing it in position for atomized development. A second exposure, to impose preprinted data or design, as shown on 45 the preprinted card, is inserted and supported on a given plane and exposed. The film can immediately be developed by application of aerated or atomized solutions thereto. Next, if desired, the double exposed image can be projected down 50 onto a sensitized card through the medium of a

lamp in the apparatus and of a condensing lens. For further clarity, sectional views of Figs. 2 and 3 show the triple procedure of making the facial exposure, the copying exposure, and the projected-image exposure on sensitized cards.

Referring now to the drawings and first to Fig. 1, the photographic apparatus comprises a cabinet 15 supported on a base 16 which forms a drainage receptacle for the apparatus. In front of and above the apparatus 15 is a chamber 17 for a lamp, a portion 17a of the lamp chamber consisting of a reflector and a portion 17b which is at the lower front being formed of glass. The lamp 17 is controlled by a momentary switch button 17c which is located at the right hand side of the base 16 next to the buttons 12, 13 and 14, to be referred to. A pair of standards 18 support the lamp chamber 17 from the forward side portions of the base 16, the standards 18 being far enough apart so that a full view of the sitter is attainable from the space between the standards. It was previously stated that the picture is taken in open daylight under a red safe-glass in full view of the sitter being photographed and of any on-looker. The red safe-glass referred to for the sitter and on-looker, is a glass strip 15a at the front inclined part of the machine and the red safe-glass for the operator is shown at 15b, the same being a part of the door 42 to be referred to subsequently. The portrait lens 19, Figs. 2 and 3, is in front of the film 20 which is mounted on a spool 21 and passes downwardly to a take-up spool 22, the two spools being connected to a belt 21a. The first facial photographic picture is taken on the area or portion 20a of the film which lies directly behind the lens 19. To operate this the operator moves a reversible lever 23 (see Figs. 1, 2 and 3) in a clockwise direction, giving to this lever a complete revolution. The movement of this lever trips the shutter 24 for the lens 19 (see Fig. 2), which exposes the negative for the facial image, and immediately after the continued movement of the lever 23 which is mounted on a roller 25 (see Figs. 2 and 3) moves the film 20 down to the position shown in Fig. 3, in focal position with respect to the projection lens 26 for producing a second exposure on the film adjacent to the portion which received the first photographic impression from the portrait lens. This movement of the film is also for the purpose of bringing the film to a position to be processed by atomizing members.

It is to be noted that a second light source consisting of a lamp 27 is at the rear of the new position of the exposed film, there being a condensing lens 28 positioned between the lamp and said position, both the lamp and condensing lens being in a separate hinged compartment 27a which permits the easy application of the film for loading purposes. The purpose of the lamp 27 and of the condensing lens 28 will be explained subsequently. For further clarity, it might be stated that the sectional view, Fig. 3, shows the triple procedure for making the facial exposure through the lens 19, for making the second exposure through the lens 26 and for projecting the images through the same lens 26 onto sensitized cards.

In the position to take the portrait through the lens 19, there is provided in front of the film a masking-out shield 30 which causes a fractional area of the negative to be exposed for the facial image. After the movement of the film downwardly, it is in position in line with the lens 26 and tubular shutter 40 and with the copying

plane for the preprinted card 31 shown in Fig. 3.

To make the second exposure from the preprinted card 31, the button 32 of Fig. 3 is first given a slight turn which moves the pin 34, see Fig. 3, into a slotted portion 35 of lever 33 and then the button connected with sliding tube 38 is pulled outwardly, which, at the same time, moves the transparent slide 36 having a blacking-out portion 37, which is designed to cover the fractional area on which the first exposure was made through the lens 19. The blacking-out area 37 can be variable in size or location, in sharp outline or vignette or design. This same outward movement of the button 32 exposes the lens 26, thus the second exposure is made on the film by a lamp 41 which illuminates the copy and which can be controlled on and off, in any suitable way, as by opening and closing a door 42 shown in Figs. 1 and 2.

The lens 26 is mounted inwardly of the slidable tubular member 38, which is connected to the button 32, and is in line with a pair of openings 39 in a stationary outer tube 40. That is to say, the movable tubular member 38 is between the lens 26 and the outer tube 40 having the openings 39. This makes the second exposure, by having first turned the button 32 and withdrawing the tube 38 from over the lens 26. Thereafter it is manually restored to normal position again, which is the means of closing the shutter for the lens 26, and this same movement withdraws the transparent slide 36 from in front of the exposed film, to permit the unobstructed and the subsequent application of atomizing solutions.

For the second exposure, I have here shown exposed to the negative the matter shown in Fig. 7 at 68a. However, this may be varied as desired in design or character of the data, finger print, etc.

The atomizing solutions are in a series of bottles 43, 44 and 45. From these bottles the solutions are adapted to be conducted upwardly to the atomizer 46 by tubes 47 leading from the bottles 45 containing the solutions and by flexible tubes 48 leading to the atomizer 46, see particularly Figs. 2 and 4. Mechanism for controlling the atomizer 46 includes the dial shaft 49 which is manually controlled by turning a small dial indicator 50 shown in Figs. 1, 2 and in the enlarged view of Fig. 4.

Mounted on the dial shaft are several cams, including a cam 51, which functions to shift the application of air from the atomizer 46 to an atomizer to be referred to presently. Also the shaft 49 is provided with three cams 52, 53 and 54 having cam lugs which are adapted to engage levers 55 to release one of the three tubes 48 so that the right solution can be applied to the film. Furthermore, the dial shaft 49 is provided with a cam 56 which is provided with three lugs which are adapted to successively engage an arm 57 which in turn is adapted to close switch contacts 58 in an electric circuit 59 leading to the air compressor which is not shown and which is exteriorly located. The tube from the air compressor is shown at 60 in Fig. 1 and also in Fig. 4. When it is desired to develop the film, the dial indicator or lever 50 is moved 90° clockwise to developing position. In doing this, the cam 56 raises the lever 57 and, in so doing, closes the switch contacts 58. This starts the operation of the air compressor so that the developing, fixing or washing solutions are sprayed on the film. When the lug of the cam passes the lever 57, there is set into

operation a time switch 61 which gives a delayed return of the lever 57 for a given length of time, for example, ten seconds, and when the period of time has elapsed, the switch 58 opens stopping actuation of the compressor. The time switch 61 is a standard article well known in the art.

Simultaneously with the 90 degree turn of the cam shaft 49, the cam 52 is first actuated, which cam actuates the lever 55 which releases the developing tube 48, thus the developer is sprayed from the tube for the given length of time which, in this instance, is ten seconds and the time switch shuts off the compressor at the end of said period opening the switch 58 and shutting off the air compressor. On again shifting the dial shaft clockwise another 90° to the fixing position, the fixing solution is released by the cam 53 for a period of time during which the fixing solution is sprayed onto the film. Then on further one-quarter clockwise movement of the lever 50, the same operation is repeated by cam 54 for the wash of the film, thus the cam shaft is moved to a position to develop, and then to fix, and then to wash.

As the hand lever 50 is moved to the first position, a lever 62 has been actuated by the cam 51 which brings a port 63 into line with the flexible tube 60 which goes to the atomizer 46. As the hand lever is moved to the two succeeding positions, the port 63 remains in engagement with the tube 60 continuing the admission of air to the atomizer 46, and on the fourth turn of the lever 50 and the dial shaft 49, the lever 62 is again restored to its inner or normal position as indicated in Fig. 4, thus again bringing the port 63a of the air intake into line with flexible tube 60a which passes to the atomizer 46a to be referred to presently.

It has previously been stated that after the first and second exposures are made on the negative, respectively through the lens 19 and through the lens 26, the positive picture will be made on a sensitized card which is in the same position as the card 31 (Fig. 3) when making the second exposure on the negative. These sensitized cards are fed from the bottom of a magazine 65 by actuating an external knob 66, which in turn actuates a roller which moves the lowermost card onto the inclined projection plane 67. In Fig. 2 I have shown one of the sensitized cards 68 in exposure position, as well as in position for the developing operation. Also, I have shown in Fig. 7 one of the finished positive pictures or cards 68. The sensitized card 68 has been exposed in the inclined plane 67 (Fig. 2) in the projection position by means of the lamp 27, the condenser lens 28 through opening 29 and the lens 26, previously referred to.

It will be understood that before the exposure on the card 68 can be made, the lens 26 is exposed by pulling out the knob 32. Next, the exposed sensitized card 68 is developed in the same position that the exposure was made, and this mechanism will now be described. The development of the exposed sensitized card 68 is by the atomizing system previously employed, using the same bottles 43, 44 and 45. It will be recalled that for the first development the solutions were supplied through flexible tubes 48, from the extensions 47 of the bottles. To develop the exposed sensitized card, flexible tubes 70 are employed and these tubes are normally closed by the inner ends of a series of hand levers 71 pivoted at 71a (Fig. 5). The operating buttons for these levers are on the exterior of the camera and are designated 72, 73 and 74. To supply the develop-

ing solution in atomized condition, I first depress the button 72, which is on one of the levers 71. This depressing of the button 72 releases the solution from the corresponding flexible tube 70. At the same time that any one of the levers 71 is depressed, it operates a lever 75 which in turn is adapted to close the circuit at the contacts 76 of the motor driven air compressor. Accordingly as long as the lever 71 having the button 72, is held depressed the developing solution is applied to the exposed card in the form of a spray. When the developing has been completed, a spring 77 restores the lever to its normal position, again closing the flexible tube 70 which supplied the developer and at the same time the switch 76 is opened, stopping the compressor. Next, the button 73 is depressed, actuating the lever 71 which in like manner supplies the atomized fixing solution to the card. After this has been supplied the requisite time, it is released, and finally the button 74 is depressed which supplies the atomized washing solution.

It will be remembered that in the first atomized developing process the atomizer is designated 46, the air being supplied by means of a tube 60 which, when the lever 62 is actuated, brings the port 63 of the tubular member into alignment with the tube 60 which supplies the air to the atomizer 46. Normally, however, with the lever 62 is the position shown in Fig. 4 the port (here designated 63a) is in register with the flexible tube 60a which leads to the atomizer 46a shown in Fig. 5, this being the atomizer used in the second developing process last described above.

This completes the development of the exposed card, which is ready to be removed either by opening the door 42 or through a slot 78, shown in Fig. 1.

I might here state that the portrait lens 24 and the feed spool 21 are in one light-tight compartment 80, while the atomizer 46, the shutter 40 and the take-up spool 22 are in another light-tight compartment, designated 81, which is adjacent the compartment 80. Also, the bottles of solutions 43, 44 and 45 are located in a separate compartment 82, closed off by a partition 83. It will be understood that all the compartments mentioned may have separate doors or movable lids by which access may be had for any purpose.

To explain further its versatile character and variable functioning, a double exposed photograph illustrated in Fig. 7 can be obtained in some instances, particularly when the device is to be operated for just plain portraiture and without special or written data, by preparing in advance the rolled sensitized film 20 with a latent pre-exposed border or design. This is accomplished by the removal of small lever 24, Fig. 2, so the lens does not open while hand lever 23 consecutively winds film to its position for second exposure, (which in this procedure is actually a first exposure).

The entire roll can be consecutively exposed to any special design or border, etc. that is placed on the copying plane, by advancing the film with each turn of the lever clockwise after each exposure. When the entire film has been pre-exposed with the aforesaid border or design, and, again rewound on spool 21 by turning the lever backwards, it can subsequently be reused in the camera, needing only the facial exposure or portrait for a completed photographic card, thus making it a time saver in actual operation or practice before a busy public. It will be seen that

in functioning in this manner, the device is only being applied specifically to straight portraiture work with a fixed pre-exposed design, already exposed in the film, and therefore would not at the same time be feasible for identification, where newly imprinted or inscribed data or numbering is required.

Mentioning further its versatile character and functioning, a double exposed photograph similar to card shown in Fig. 7 can be obtained without a preprinted registration card, or a second exposure to copy same. As generally known in regular portraiture work, a photograph is desirable with a bordered embellishment and, say, the name of the studio or the photographer for illustration. This is accomplished with my invention by having any design or embellishing matter permanently and specially fixed on the transparent slide, which as already described is pushed in front of the exposed section just before the tubular shutter opens. By merely opening tubular shutter on a blank lighted space on the copying plane, the light transmitted through the lens 26 passes through the transparent slide, and exposes upon the unexposed area of the film whatever image is designed or fixed on the slide. Then when the shutter is closed and the slide is moved back the exposed portion is developed in the same manner as before. This is illustrated in Fig. 10 wherein the slide 36a is shown as having an inner border portion 36b, an outer border portion 36c outside of the black-out section 37.

Thus it will be seen that the objects stated in the early part of the specification are very effectively attained with the present invention, with the alternative of making the second exposure without exposing from the preprinted card.

I do not desire to be confined to the precise details shown, but aim in my claims to cover all modifications which do not involve a departure from the spirit and scope of the invention.

Having thus described my invention, I claim:

1. In a photographic apparatus including a housing, a camera therein having a shutter and lens, means for moving a sensitized strip in photographing relationship to said camera, and a window in said housing in alignment with said lens; the improvement which comprises the pro-

- 5 vision of means for exposing to said camera a fractional area only of said strip, a second lens and shutter within said housing, a slide within said housing and having an opaque area and a transparent area, means for moving said slide just prior to the opening of said second shutter to position the opaque area of the slide over the fractional area of the strip which was exposed during the first exposure and the transparent 10 area of the slide over the unexposed portion of the strip, means for advancing the strip from its photographing position relative to said camera to a photographing position before said second lens for a second exposure thereon adjacent the first exposure, and means within said housing for developing simultaneously the two exposed portions of the strip while the strip remains in the position it occupied during the second exposure.
2. Photographic apparatus as defined in claim 20 1 and wherein means is provided within the housing for projecting the developed negative image produced by the two exposures onto a sensitized element for the purpose of producing a positive image of the two exposures.
- 25 3. Photographic apparatus as defined in claim 1 and wherein means is provided within the housing for presenting preprinted matter to said second lens to constitute the subject matter of the second exposure.

30
